UNITED STATES PATENT OFFICE.

CHRISTOF BACHMANN, OF BAGBY, CALIFORNIA.

SECTION-HOLDER FOR HIVES.

1,103,467.

Specification of Letters Patent. Patented July 14, 1914.

Application filed March 23, 1914. Serial No. 826,519.

To all whom it may concern:

Be it known that I, CHRISTOF BACHMANN, a citizen of the United States, residing at Bagby, in the county of Mariposa and State 5 of California, have invented new and useful Improvements in Section-Holders for Hives, of which the following is a specification.

This invention relates to a holder for bee-hives, and particularly to a holder for comb-frames, means being provided whereby the holder may be quickly and easily opened to receive the comb-frames, and which holder is provided with a simple, practicable and substantial clasp whereby the holder may be 15 tightly locked or bound upon the inserted frames.

It is a particular object of the present invention to provide a comb-frame holder which has a movable side having a binder 20 or locking device which provides for the secure closure of the holder upon the included frames and which permits the opening of the holder to release the frames without any actual handling of the frames.

The invention consists of a comb-frame holder, with a movable side, and means for connecting the side to the holder so as to permit the ready insertion and removal of comb-frames in the holder and which provides a practicable clamp and lock at once connecting the movable side to the holder proper and providing for the compact and snug locking of a multiplicity of the comb-frames.

It also comprises details of construction which will be more fully explained by reference to the accompanying drawings, in which—

Figure 1 is a side elevation of the holder, 40 showing the frames adjusted and the movable side in relatively open position. Fig. 2 is an edge view from one end of the holder. Fig. 3 is a detail plan view of the fulcrum or shoulder of the locking device.

The holder is shown as comprising, in the present instance, a substantially rectangular main part or frame 2, the lower rigidly connected corners 3 of which are bound by metal corner binders 4. The holder 2 is adapted 50 to receive a multiplicity of given sized comb-frames 5, it being understood that the holder 2 may be made of such proportions as to receive any desired number of the comb-frames.

It is one of the purposes of the present in-

vention to provide a holder within which the comb-frames may be readily and quickly adjusted with as little actual fingering or handling as possible to avoid soiling, and which holder includes means for firmly locking the 60 comb-frames in position so as to prevent their play or dislocation after insertion in the hive.

The holder is provided on one side with a relatively movable side piece 6, which may be of suitable length and, if desired, allowed to project over the adjacent perpendicular sides of the holder 2 to form ledges adjustable upon coördinate supports in the hive. The relatively movable side bar 6 is provided on each of its ends with a spring link 7, here shown as substantially U-shape, the transverse bar of which extends through and is pivoted in the ends of the holder side 6. The side arms of the spring links 7 are 70 slightly bent and provided at their outer or swinging ends with eyes 8 in which is substantially centrally pivoted a lever 9. The lever 9 is shown as formed of bent wire with substantially parallel side arms 10 provided with eyes 11 coacting with the eyes 8 of the spring link 7; the ends of the lever being transversely connected by an abutment rod 12 and the cut ends of the wire being brought together in a twist 13 to form not only a 80 rigid brace and connection between the parallel arms 10 of the lever 9 but also to form a substantial handle or finger piece.

The upper outer surfaces of the parallel fixed sides of the holder 2 are each provided with an abutment plate 14 suitably secured to the material of the holder and having an angular transverse shoulder 15, the top of which is flush with the contiguous ends of the box side. The abutment shoulder 15 is 90 centrally nicked or slotted, as at 16, to form a seat for a complementary horn 17, attached to the coöperative end of the removable side 6 of the holder. These horns, when the side 6 is adjusted upon the holder 2, are adapted 95 to register with the nicks or slots 16 and not only guide the parts relatively, but also prevent lateral movement of the side as to the holder.

In practice, after the comb-frames 5 have 105 been arranged within the holder 2, the operator then adjusts the abutment bar 12 of one of the levers 9 against and beneath the transverse abutment shoulder 15, at one of the upper corners of the holder 2, and moves 110

the removable side 6 into a relative closing position along the open side of the holder. He then swings the lever 9 downwardly about the fulcrum or abutment shoulder 15, thus placing its swinging spring link 7 under tension in its bowed arms as the outer ends of the links swing about their fulcrum in the side members 6 with the downward swinging movement of the lever 9, the inner 10 end of which reacts against the abutment shoulder 15 until, when the lever 9 is finally swung to the closed and locking position at the left of Fig. 1, the fulcrum of the link 7 is well to one side of the abutment 15, with 15 the pivotal end of the lever 9 resting firmly against the ledge 15. The other locking device at the opposite end of the movable member 6 is then closed by adjusting the swinging end 12 of the lever 9 under its respective abutment or fulcrum ledge 15. As 20 the lever 9 is swung downwardly it springs or bows its link 7 as the fulcrum eyes 8-11 pass the center line through the fulcrum of the link 7 and the abutment ledge 15; the lever 9 swinging firmly into closed 25 position against its adjacent side of the holder 2 when in final locking position. From this it can be seen that I have provided means whereby a removable side or 30 end of a comb-frame holder may be quickly attached and removed, and which means provides for firmly closing the holder upon the included comb-frames, the locking device being simple, practicable, easily operated and comparatively inexpensive.

The ends of the removable member 6 may be bound with metal rings 18, upon which, in the present instance, the registering and centering horns 17 are integrally 40 formed and in which rings 18 the pivotal bars of the respective springs links are mounted.

Having thus described my invention, what

I claim and desire to secure by Letters Patent is—

45

1. The combination with a honey-comb frame holder having a movable side, of a fastener for temporarily locking the movable side to the holder, said fastener comprising a spring member connected to one of said parts, and a lever member fulcrumed to the spring member and coöperable with the other of said parts for locking the parts in relatively closed position.

2. The combination in a honey-comb frame holder, of a main holder body open at one side, a movable side operable to close the open side of the holder, a swinging spring member connected to the movable side and carrying a locking member, and a shoulder on the holder body coöperating with said locking member and said spring member to hold the movable side in closed locked position upon the holder.

3. The combination in a honey-comb frame holder, of a main body part open at one side, a movable closure, abutments mounted upon the body part adjacent to the ends forming the opening, a locking device carried by said movable closure comprising a link with parallel, substantially bowed arms and pivoted in said movable member, and a lever fulcrumed in the outer swinging ends of the bowed link, one end of said lever being adjustable against its respective abutment and operative thereupon, when swung downwardly thereabout, to tension the bowed link as said lever is swung about the abutment.

In testimony whereof I have hereunto set my hand in the presence of two subscribing witnesses.

CHRISTOF BACHMANN.
